UNITED STATES PATENT OFFICE

JOHN C. CROMWELL, OF ALLIANCE, OHIO, ASSIGNOR TO THE STEEL SANITARY COMPANY, OF ALLIANCE, OHIO, A CORPORATION OF OHIO

METAL-TRIMMING METHOD

Application filed June 16, 1928. Serial No. 286,029.

The present invention deals more particularly with the art of sheet metal ware making and sheet metal working, and especially refers to an improved method and apparatus for trimming edges of sheet metal shapes or sections preparatory to the welding thereof. I have found that extremely desirable results may be effected by the utilization of a high speed saw so mounted as to be effective for cutting in a substantially horizontal plane, and supporting the material in such manner as to provide for relative movement between the saw and the support in addition to the movement of the saw itself.

In the accompanying drawings there are shown for purposes of illustration only, certain preferred embodiments of the present invention, it being understood that the drawings do not define the limits of my invention either with respect to the material treated or with respect to the construction of the apparatus utilized.

In the drawings:—

Figure 1 is a side elevational view of one form of apparatus constructed in accordance with the present invention;

Figure 2 is a top plan view of the construction illustrated in Figure 1;

Figure 3 is a transverse vertical sectional view on the line III—III of Figure 1, looking in the direction of the arrows;

Figure 4 is a detail sectional view on the line IV—IV of Figure 3;

Figure 5 is a view similar to Figure 3 illustrating a slightly different embodiment of the invention; and

Figure 6 is a detail sectional view on the line VI—VI of Figure 5.

Figure 7 is a view in elevation of a completed tub, delineating the length of junction of the sections which enter into the building up of the same.

In accordance with the present invention I provide a bed 2, having guide rails 3 thereon, adapted to accurately guide and position a support 4 in the general form of a platen adapted to move thereover. The platen is preferably constructed of magnetic material, adapted to hold in position thereon and against possibility of relative movement, any

metal placed on it. It also preferably has its upper surface shaped as desired to receive and support previously formed sections, two of which are illustrated in position thereon.

In practice, the sections are shaped in any desired manner, and then placed in position on the support in such manner that the support is effective adjacent the proposed plane in which it is desired to effect trimming of the edges, thereby preventing any distortion of the edges during trimming. In the case of cup shaped sections 5, supplemental filler blocks or anvils 6 may be dropped into position to further support the same during trimming.

For trimming purposes I preferably provide a high speed saw so mounted as to keep the cutting edge thereof effective in a substantially horizontal plane and in substantially the plane of the upper surface of the holder 4. In Figures 1, 2 and 3 of the drawings I have illustrated a high speed saw 7 of the circular type, while in Figure 5 of the drawings there is shown a high speed saw 8 of the band saw type. Where a circular saw is utilized, it will preferably be of concave contour on its lower surface, as clearly indicated in Figure 3 of the drawings, thereby to provide a downwardly projecting cutting edge directed into and against the metal to be trimmed.

The saw may be mounted directly on the armature shaft of a suitable driving motor 9, supported for adjustment on a pedestal 10, as illustrated in detail in Figure 4 of the drawings, in which the motor frame and pedestal are shown as provided with dove-tail shaped inter-engaging portions 11, with which cooperates a threaded shaft 12, providing for vertical adjustment of the motor and saw.

In the form of Figures 5 and 6 of my invention, there is illustrated a high speed saw 8 of the band saw type, traveling around disks 13 and 14, mounted at spaced points in a suitable U-shaped frame 15. Carried by the frame for driving one of the disks is a motor 16, preferably directly connected to the disk with which it cooperates. The entire frame 15 in turn cooperates with a pedestal 10', 100

similar to the pedestal 10, and mounted for vertical movement thereon through the connections illustrated in Figure 6 of the drawings.

With the construction shown, it will be apparent that there is provided a saw effective in a substantially horizontal plane and capable of being vertically adjusted to control the exact plane of cutting. The saws in both cases cooperate with supporting means effective for maintaining the edges of a pre-shaped section against the possibility of distortion, and for permitting bodily relative movement between the saw and the supporting means. Due to this construction, the saw in either case operates in effect as a planer, but has a materially greater capacity than a planer, especially when used for trimming the edges of relatively thin sheet metal sections. In actual practice it has been found that extremely satisfactory trimming results may be obtained by effecting such a relative movement between the metal and the saw as to produce a trimming of from six to fifteen feet a minute. In this manner, a complete section of irregular contour having upstanding edges to be trimmed in a common plane may be completely and accurately trimmed at a single movement of the platen. With a saw of the circular type, the stroke of the platen in one direction will be effective for producing a trimming operation of a supported article at one side of the saw, while the return movement may be utilized for effecting a similar operation on another article at the opposite side of the saw, both strokes of the platen thus becoming working strokes contrary to the usual operation in the planer. With a band saw, I have found it desirable to provide one idle stroke on the platen due to the difficulties of accurately supporting a band saw having cutting teeth on both edges thereof.

After the edges of the sections have been trimmed in the manner referred to, adjacent edges of different sections may be brought together in such manner that they accurately abut to facilitate welding thereof, and then welded in accordance with any of the well-known methods.

The present invention thus has the advantages of replacing the relatively slow planing operations by a high speed operation capable of simultaneously operating on a plurality of spaced edges of one or more sections so as to completely shape one or more sections at a single operation. This insures absolute uniformity between successive trimmed sections, facilitating the after operations of assembling and welding.

It will be apparent to those skilled in the art that changes in the construction and operation herein disclosed may be made without departing either from the spirit of my invention or the scope of my broader claims.

I claim:

1. In the method of welding, the steps comprising shaping a section of sheet metal, supporting the shaped sheet against displacement, sawing the edges thereof while so supported, and then subjecting the section to a welding operation. 70
2. In the method of metal trimming, the steps comprising shaping a section of sheet metal, supporting the shaped section, and trimming the edges thereof by sawing while so supported. 75
3. In the method of trimming, the steps comprising placing the article to be trimmed on a support, bringing the article while so supported and a saw into cooperative relationship, driving the saw, and producing relative movement between the saw and the support while the saw is so driven. 80
4. In the method of welding, the steps comprising shaping a section of sheet metal to provide upstanding edges, supporting the shaped section, trimming the edges thereof while so supported, and then subjecting the trimmed section to a welding operation. 85

5. In the method of working metal, the steps comprising shaping a metal section to provide upstanding edges, supporting the shaped section, effecting bodily movement of the shaped section while so supported, and trimming all of said edges during such movement by subjecting them to a sawing operation. 90

In testimony whereof I have hereunto set my hand.

JOHN C. CROMWELL.
